HOSPITAL BEDRAIL COUNTERBALANCE UNIT
Frederick D. Wright, 1229 Maddox St.,
Long Beach 10, Calif.
Filed Nov. 17, 1961, Ser. No. 152,988
8 Claims. (Cl. 5—92)

The present invention relates generally to the field of hospital accessories, and more particularly to an improved bedrail counterbalance unit that permits a bedrail to be raised and lowered with a minimum of physical exertion.

A relatively recent development in hospital beds is to provide a cabinet that is mounted on one of the bedrails, with this cabinet being adapted to house such items as a radio, telephone and storage space for a patient's toilet articles and other accessories. Such cabinets may weigh from thirty to forty pounds, and inasmuch as they are mounted on the bedrails, they move upwardly and downwardly with the rails as they are pivoted from a protective position to a non-protective position on the hospital bed. Due to the combined weight of the cabinet and the bedrail structure, it is a not uncommon occurrence for the bedrail supporting the cabinet to slip from a nurse's hands during manipulation of the bedrail whereby the cabinet falls to the floor, causing severe damage thereto. Although the cabinet as above described is a distinct convenience for the patient, the combined weight of the cabinet and bedrail works a hardship on the attending nurses in moving the cabinet-supporting bedrail from a downwardly non-protective position to an upwardly protective position where the bedrail protects the patient and also places the cabinet in an operative position where it may be utilized by the patient.

A major object of the present invention is to provide a mechanism that may be removably mounted on a hospital bed equipped with a bedrail that supports a cabinet of the character described, with the spring action of this mechanism compensating for the combined weight of the bedrail and cabinet mounted thereon to permit the same to be pivoted either from a protective to a non-protective position or vice versa, with a minimum of physical exertion.

Another object of the invention is to supply a device that can be used with a hospital bedrail, irrespective of whether a cabinet is supported therefrom, whereby the physical effort required to manipulate the bedrails is reduced to a minimum.

A still further object of the invention is to provide an extremely simple mechanism which is easily mounted on a conventional hospital bed to compensate for the weight of the bedrail irrespective of the positioning thereof, requires a minimum of maintenance attention, and can be fabricated from standard, commercially available materials whereby it can be sold at a sufficiently low price as to encourage its widespread use in hospitals, sanitariums and like institutions.

A further object of the invention is to provide a device that counterbalances a bedrail with a cabinet mounted thereon to the extent that nurses do not violate the state health and safety laws relative to lifting when they pivot the bedrail to an up or down position.

These and other objects and advantages of the invention will become apparent from the following description of a preferred form thereof, and from the accompanying drawing illustrating the same, in which:

FIGURE 1 is a perspective view of a conventional hospital bed equipped with bedrails, on one of which a cabinet is supported, with the weight of both of the bedrails as they are pivoted between an up and down position being compensated for by the counterbalance unit of the present invention mounted on the headboard of the bed;

2

FIGURE 2 is an exploded perspective view of the counterbalance unit shown in FIGURE 1, from which the cover has been removed;

5 FIGURE 3 is a front elevational view of the counterbalance unit shown in FIGURE 2, from which the cover has been removed;

FIGURE 4 is a top plan view of the unit illustrated in FIGURE 1 with portions thereof being broken away to show the interior of the invention;

10 FIGURE 5 is an enlarged side elevational view of that portion of the unit shown on the right-hand side of FIGURE 3;

15 FIGURE 6 is a fragmentary vertical cross-sectional view of the counterbalance unit taken on line 6—6 of FIGURE 1;

FIGURE 7 is a vertical cross-sectional view of the unit taken on line 7—7 of FIGURE 9;

FIGURE 8 is a horizontal cross-sectional view of a portion of the unit taken on line 8—8 of FIGURE 3;

20 FIGURE 9 is a perspective view of an end portion of a hospital bed on which one of the bedrail counterbalance units is mounted;

25 FIGURE 10a is a perspective view of a first component used with an anchor forming a part of the unit;

FIGURE 10b is a perspective view of a second component of the anchor.

With continuing reference to the drawing for the general arrangement of the invention, it will be seen that 30 the counterbalance unit, generally designated by the letter A is mounted on the headboard B of a conventional hospital bed C, best seen in FIGURE 1. The bed C includes a footboard B' that is of the same general structure as headboard B. Headboard B comprises two vertical 35 corner posts E, a lower cross piece F that rigidly connects the posts, and a longitudinally extending member G which connects the cross piece F and similarly situated cross piece (not shown) forming a part of the footboard B'.

40 A cross member H connects the upper portions of the posts E, as best seen in FIGURE 1. A panel J of substantial depth extends transversely between the post E and is rigidly affixed thereto. Panel J (FIGURE 1) is set inwardly a substantial distance from the forwardmost surfaces of the posts E. The posts E have downwardly extending members K which are adjustably supported therein by means (not shown), which members terminate in bifurcated arms 10 between which a shaft 12 extends and on which a resilient roller 14 is supported. The footboard B' is of substantially the same structure as the 45 headboard B and need not be described in detail herein. The component parts of the footboard B' are identified by the same letters and numerals used in conjunction with headboard B, to which a prime has been added for the sake of clarity. A mattress L is supported between the headboard B and footboard B' by conventional means 50 (not shown).

The bed C may best be seen in FIGURE 1, and is provided with two bedrails, with the bedrail on the left-hand side of the bed being identified by the letter M and the right-hand rail by the letter M'. The bedrails M and M' are identical in construction, with the exception that at substantially the upper center of bedrail M a cabinet N is supported that contains a radio, telephone, storage space for toilet articles and the like, that may be needed by a patient occupying the bed on which the bedrail M is mounted. Bedrail M includes a longitudinally extending rigid tubular member 15 that curves downwardly on the ends thereof to define two legs 17 having inwardly 55 projecting extensions 18 which are pivotally supported by pins 16. The pins 16 are mounted on brackets 19 that are affixed to the cross pieces F, as may best be seen in

70

FIGURES 1 and 9. Tubular member 15 has two longitudinally spaced arms 15a extending upwardly therefrom which have longitudinally positioned bores formed in the upper ends thereof that are engaged by pins 20.

The pins 20 also engage the lower ends of two uprights 22 that have upper and lower rigid members 24 and 26 extending therebetween as may be seen in FIGURE 1. The upper member 24 has an extension 24a that projects toward the headboard B, also shown in FIGURE 1. A longitudinally extending tapped recess 27 is formed in extension 24a, as may best be seen in FIGURE 6.

A connector 28 is provided, the function of which will be explained hereinafter. Connector 28 (FIGURE 6) comprises a cylindrical body 30 having a threaded projection 32 that engages the tapped recess 27. An elongate member 34 having a bore 36 formed therein that extends transversely therethrough is gripped between the adjoining ends of extension 24a and body 30 when the threaded projection 32 engages tapped recess 27 as shown.

A hook-shaped member 38 is provided for each of the members 34, each of which is pivotally supported on an inwardly disposed end of one of the members 34 by a pin 39. Due to the force of gravity, members 38 pivot to a position where they engage pins 40 that project outwardly from posts E, and when so engaged, these pins serve to hold the bedrails M and M' in the upwardly extending position shown in FIGURES 1 and 9. When the hook-shaped members 38 are disengaged from the pins 40, the bedrails M and M' may be pivoted downwardly to occupy the position shown in phantom line in FIGURE 1. The body 30 has a longitudinally extending cavity 42 formed therein as well as a tapped transverse bore 44 that is in communication with this cavity. A screw 46 is mounted in the tapped cavity 42.

The counterbalance unit, as may best be seen in FIGURE 3, includes two arms P and P' that extend upwardly and outwardly in opposite directions therefrom. Slots 48 and 48' are formed in the outer extremities of arms P and P'. The slot 48 can be engaged by a fastener 50 that includes a head 52 from which a shank 54 extends. Shank 54 passes through the slot 48 and thence through a washer 56 to snugly engage the cavity 42. Shank 54 has a flat area 58 formed on one side, which flat area may be pressure-contacted by the interior end of the screw 46 to hold the fastener in a fixed position within the confines of cavity 42. The same structure just described is also utilized in connecting the arms P' to the end portion of the bedrail M' most adjacent the headboard B.

The counterbalance unit also includes a housing 60, best seen in FIGURES 2 and 3, that is defined by a transversely extending web 62 to an upper flange 64 and lower flange 66 that projects therefrom. Flange 66 has a rectangular recess 68 formed in the outer part of each end portion thereof. Flange 66 also has an extension 70 that projects upwardly from the outer longitudinal edge thereof between the recesses 68.

A cover 72 is provided for housing 60 which includes a rectangular vertical member 73 having an upper flange 74 and lower flange 76 projecting inwardly therefrom. Flanges 74 and 76 are so spaced as to slidably but frictionally engage the flanges 64 and 66 to removably hold the cover 72 in place on housing 60. The flange 74 has elongate recesses 78 formed in the end portions thereof (FIGURE 2) that are in vertical alignment with the recessed portions 68 when the cover 72 is mounted on flanges 64 and 66. Flange 76, as may be seen in FIGURE 2, is shorter than flange 66 and does not extend over recesses 68 when cover 72 is mounted on housing 60 as shown in FIGURE 4. When the cover 72 is removably mounted on the flanges 64 and 66, the interior surface of vertical member 73 is outwardly disposed from the exterior surfaces of the posts E most adjacent thereto. It will be noted that when the cover 72 is so mounted, the

arms P and P' project upwardly through slots 78 (FIGURE 1).

The flange 64, as may best be seen in FIGURE 2 has an annular U-shaped slit formed therein. The portion of flange 64 within the confines of this slit is bent downwardly to define a longitudinally extending tongue 80 that is adapted to removably engage an anchor assembly 82, the details of which are shown in FIGURES 3, 10a and 10b. An opening 84 is formed in flange 64 adjacent the tongue 80. A tongue 86 similar to tongue 80 in form but of heavier structure, is welded or otherwise affixed to the interior surface of flange 66 as shown in FIGURE 3. The tongue 86 serves to removably support an anchor assembly 82 on flange 66, but oppositely disposed to the anchor assembly engaged by tongue 80.

Each anchor assembly 82, as may best be seen in FIGURES 3, 10a and 10b, includes a mounting member 88 and anchor member 90. The mounting member 88 includes two identical parallel side walls 92 that are connected by a cross piece 94 and an angularly disposed end piece 96. The side walls 92 have two pairs of slots 98 and 100 formed therein, and end piece 96 has a centrally disposed bore 102 formed therein.

The anchor member 90 includes two parallel links 104 having transversely aligned bores formed therein that are pivotally engaged by first and second cross members 106 and 108. The cross members 106 and 108 have projecting end portions 106a and 108a that are slidably mounted in slots 98 and 100 respectively. A screw 110 extends through opening 102 and engages a tapped bore formed in cross member 106. Screw 110 includes an Allen head 112. When the anchor member 90 is disposed inside mounting member 92, the anchor assembly is supportable from either flange 64 or 66 by causing the tongue 80 or 86 to slidably engage the cross piece 94 as shown in FIGURE 3. By rotating Allen head 112 when it is in contact with end piece 96, the anchor member 90 can be caused to move towards or away from end piece 96 for reasons that will later be explained. The Allen head 112 can be rotated by a suitable tool (not shown) that is extended through opening 84 or a similar opening (not shown) formed in flange 66.

Cross member 108, as can best be seen in FIGURE 10b, has a bore 114 extending transversely therethrough. A first helical spring 116 is provided that has first and second hooks 118 and 120 respectively formed on the ends thereof. First hook 118 removably engages bore 114 of the anchor assembly 82 supported from flange 66 as shown in FIGURE 3. The second hook 120 engages a loop 122 formed on one end of a cable 124 that extends upwardly to the left as illustrated in FIGURE 3. A rigid ball 126 is mounted on the other end of cable 124.

When the bedrails M and M' are in the upwardly extending protective position shown in FIGURE 1, first portions 128 and 128' of arms P and P' respectively, extend downwardly and inwardly towards one another, and are disposed at approximately a 45° angle relative to the vertical. With arms P and P' in this position, second portions thereof 130 and 130' respectively, are vertically disposed, as may best be seen in FIGURE 3.

A first cam member 132 is rotatably supported on a shaft 134 that extends between web 62 and the vertical extension 70. A lug 136 is welded or otherwise affixed to the shaft 134 and is also rigidly connected by welding or other fastening means (not shown) to the extension 70, to prevent rotation of shaft 134. The first cam member 132, as may be seen in FIGURE 3, is elongate, and the shaft 134 passes through a bore formed in the lower end portion thereof.

The upper portion of the cam member 132 is curved, and the outer portion thereof develops into two laterally spaced lugs 138, as best shown in FIGURE 8, that have upwardly and inwardly extending lower surfaces which grip the upper surface of the ball 126 when it is in pres-

sure contact therewith. The upper portion of the first cam member 132 slopes downwardly and develops into an inwardly disposed surface 140 that is substantially straight, as may be seen in FIGURE 3.

The second portion 130 of arm P is affixed to that side of the cam member 132 most outwardly disposed from the headboard B by bolts 142 or other fastening means. The cam member 132 has a groove 144 formed therein (FIGURE 4) that can be engaged by the cable 124 as the arm P pivots from the upper position shown in FIGURE 3 to the lower position shown in phantom line in the same figure. The position of the first cam member 132 when the arm P is in the downwardly extending position is also shown in FIGURE 3 in phantom line.

When it is desired to move the bedrail M from the upwardly extending position shown in solid line in FIGURE 1 to a downwardly disposed position shown in phantom line in the same figure, the fastening member 38 is disengaged from the pin 40, and the bedrail M moved downwardly into the desired position. It will be particularly noted that while the legs 17 move through approximately 180° from the upwardly extending position to the downwardly extending position, the arm P only rotates through approximately 90°. As the bedrail M moves from the up position towards the lower position, the weight of the bedrail M and cabinet N supported by the arm P decreases. During this downward rotation of the bedrail M and cabinet N, the spring 104 which is initially under tension, exerts an increasing tensional force on the arm P.

Due to the elongate shape of the first cam member 132, the lever arm between the center of rotation of the first cam member, and that portion thereof just contacted by the cable 124 as the arm P rotates in a counter-clockwise direction, decreases. However, this decrease in the effective lever arm is so calculated relative to the increasing force effected by the deforming spring 116, that a substantially constant upward force is exerted on the bedrail M and cabinet N as the rail and cabinet move from the upright to the downwardly extending position shown in phantom line in FIGURE 1. Thus it will be seen that while the tensional force exerted by the spring 116 varies and increases as it deforms longitudinally due to rotation of the cam member 132 and arm P, a variable upward force is exerted on the bedrail M and cabinet N during such movement due to the shape of the cam member 132 that is just sufficient to balance the bedrail M and cabinet N in the particular position to which it has been moved.

A second helical spring 150 is provided that has a first curved end portion 152 which engages opening 114 in the anchor assembly 82 supported on flange 60 as shown in FIGURE 3. Spring 150 includes a second curved end portion 154 that is connected to a loop 156 on a cable 158 which terminates in a second ball 160. The ball 160 is removably gripped between two laterally spaced lugs 162 which are arranged in the same manner as the lugs 124 previously described. Lugs 162 are formed on a second cam member 166, as may best be seen in FIGURE 5.

The second portion 130' of arm P' is affixed to the outer face of the second cam member 166 by bolts 168 or other suitable fastening means. A shaft 170 extends transversely between the web 62 and extension 70, as shown in FIGURE 3. A lug 172 is welded to the under side of the shaft 170 and rigidly affixed to the extension 70 to prevent rotation of the shaft. Shaft 170 extends through a transverse bore 174 formed in the lower portion of the second cam member 166. The second cam member 166 has an upper portion, one side of which slopes downwardly and outwardly towards the lugs 162, and against which a portion of the cable 158 bears when the ball 160 engages the lugs 162.

The second cam 166 has an edge surface 176 in which a groove 178 is formed that engages the second cable 158

as the arm P' pivots from the upwardly extending position shown in solid line in FIGURE 3 to the lower position shown in phantom line in the same figure. The arm P' in cooperation with the spring 150 and second cam 166 serves the same purpose for the bedrail M' as that of the previously described portion of the counterbalance unit for bedrail M with the cabinet N supported thereon.

It will be apparent that the bedrail M' does not include the cabinet N and is therefore considerably lighter in weight. Accordingly, the spring 150 used in conjunction therewith may be one that exerts substantially less force when longitudinally deformed than the spring 116, yet still support the bedrail M' at any desired position by means of arm P'. The counterbalance unit is preferably affixed to the panel J as shown in FIGURE 1 by bolts or screws (not shown) that extend through bores 180 in web 62.

The cams 132 and 166 are interchangeable and can be used on desired sides of the invention. The lugs 138 and 162 contact the flange 66 when the bedrails M and M' are in the fully down position and accordingly also function as stops.

In FIGURE 2 it will be noted that there is a second tongue 80' and opening 84' to the right of tongue 80 and opening 84. Also, in FIGURE 3 it will be seen that there is a second tongue 86' to the left of tongue 86. This construction permits the anchors 82, springs 116 and 150, and the arm assemblies P and P' to be reversed to allow the bedrail M and cabinet N to be mounted on the right-hand side of the bed as viewed in FIGURE 1, and the bedrail M' on the left-hand side thereof.

The operation of the invention has been described in detail hereinabove and need not be repeated.

Although the present invention is fully capable of achieving the objects and providing the advantages hereinbefore mentioned, it is to be understood that it is merely illustrative of the presently preferred embodiment thereof and I do not mean to be limited to the details of construction herein shown and described, other than as defined in the appended claims.

I claim:

1. A counterbalance unit for balancing the weight of a bedrail pivotally supported in a longitudinally extending position along one side of a hospital bed and extending between the headboard and footboard thereof, said bedrail including at least one longitudinally extending rigid member and being capable of occupying a first upwardly extending protective position and in any one of a number of second non-protective positions in which it is disposed outwardly from said bed a greater distance than when in said first position, said unit comprising: a rigid arm having first and second end portions; means for pivotally connecting said first end portion of said arm to said rigid member; means for removably holding said bedrail in said first position; a housing; means for supporting said housing from said headboard; an elongate cam member having first and second end portions and a bore formed therein that extends transversely through said cam member adjacent said second end portion; a shaft supported from said housing that extends through said transverse bore and pivotally supports said cam member; means supporting said second end portion of said arm from a side of said cam member and normal to said shaft; a cable having first and second end portions; means for affixing said first end portion of said cable to said cam member, with a part of said cable adjacent said first end portion extending over said first end portion of said cam, with said first end portion of said cam being upwardly disposed when said bedrail is in said first position; and spring means in said housing connected to said second end portion of said cable for exerting a force of constantly increasing magnitude on said cable as said cam member pivots due to movement of said bedrail from said first to one of said second positions, with said cam being of such shape that as it pivots to increase said force on said spring only that

portion of said force required to counterbalance said bed-rail in the particular one of said second positions in which said bed-rail may be disposed is transferred to said arm.

2. A counterbalance unit as defined in claim 1 wherein said means for pivotally connecting said first portion of said arm to said rigid member is an elongate cylindrical body having a cavity extending longitudinally therein from a first end thereof as well as a tapped transverse bore which communicates with said cavity, and further includes an extension of said body that projects from a first end thereof, said extension having threads formed on the exterior surface thereof, which threads engage threads formed in a tapped bore formed in an end portion of said rigid member; a screw that engages said threads in said tapped bore; an elongate fastener that is insertable in said cavity formed in said cylindrical body; and a head mounted on the outer end of said fastener, said fastener extending through an opening formed in said first end portion of said arm, with said screw when tightened, engaging a flattened recessed portion of said fastener to hold the same in said bore to maintain said arm in pivotal engagement with said fastener during such time as said fastener is held in said cylindrical body by said screw.

3. A counterbalance unit as defined in claim 1 which in addition includes anchor means mounted in said housing, with said second end portion of said spring connected thereto.

4. A counterbalance unit as defined in claim 1 which in addition includes anchor means removably mounted in said housing, with said second end portion of said spring connected thereto.

5. A counterbalance unit as defined in claim 1 which in addition includes manually adjustable anchor means mounted in said housing, with said second end portion of said spring connected thereto, and an opening in said housing to permit adjustment of said anchor means for varying the tension on said spring.

6. A counterbalance unit as defined in claim 1 which in addition includes manually adjustable anchor means removably mounted in said housing, with said second end portion of said spring connected thereto, and said anchor means capable of occupying either of two positions in said housing to allow said unit to be with said bed-rail when mounted on either side of said bed.

7. A counterbalance unit as defined in claim 2 wherein said housing is defined by an elongate transverse web disposed adjacent said headboard, and further includes two flanges that extend outwardly from the longitudinal edges of said web, a cover that slidably engages said flanges to removably hold said cover in place thereon, which cover and flanges have recessed end portions that cooperatively define a slot through which said arm projects, with said slot permitting the pivotal movement of said arm as said bed-rail moves from said first to one of said second positions.

8. A counterbalance unit as defined in claim 2 wherein said means for affixing said first end portion of said cable to said cam member comprise two laterally spaced lugs formed on the side of said cam member opposite that side which will be contacted by said cable when said cam member is rotated by said arm as said bed-rail moves from said first to one of said second positions, which unit further includes a rigid ball mounted on said first end portion of said cable that removably engages the under sides of said lugs.
